UNITED STATES PATENT OFFICE.

ALFRED L. EUSTICE, OF CHICAGO, ILLINOIS, ASSIGNOR TO ECONOMY FUSE & MANUFACTURING COMPANY, OF CHICAGO, ILLINOIS, A CORPORATION OF NEW YORK.

INCLOSED SAFETY-FUSE.

1,270,391.

Specification of Letters Patent. Patented June 25, 1918.

Application filed May 3, 1915. Serial No. 25,344.

To all whom it may concern:

Be it known that I, ALFRED L. EUSTICE, a citizen of the United States, residing at Chicago, in the county of Cook and State of Illinois, have invented certain new and useful Improvements in Inclosed Safety-Fuses, of which the following is a specification.

My invention relates to cartridge fuses 10 for the protection of electrical circuits, and refers particularly, although not exclusively, to renewable cartridge fuses of the so-called ferrule type.

In my co-pending application, Serial No. 15 852,557, filed July 23, 1914, I have described a cartridge fuse in which the ferrules located at the ends of the insulating casing are provided with inwardly-extending abutment flanges, which, in turn, are engaged 20 by apertured washers through which the ends of the fusible link extend, these ends being clamped in position and the washers being forced into firm engagement with the abutment flanges by means of plugs which 25 screw into the ends of the ferrules.

I have found that considerable difficulty and expense are entailed in the manufacture of ferrules of the type just described which have inwardly-extending abutment flanges 30 formed integral therewith, and it is one of the objects of my invention to increase the simplicity of manufacture, and thereby decrease the cost by constructing the ferrules with separate abutment thimbles, on each of 35 which is formed an inwardly-extending abutment flange, the abutment thimbles being assembled with sleeves of the ferrules so that in their adjusted position a unitary structure is formed.

40 A further object of my invention consists in the provision of means by which the washers at the end of the fuse will be aligned in predetermined positions so that the fuse link which extends between these washers 45 must be maintained in proper position with respect to the fuse casing.

A still further object of my invention consists in improved means for attaching the ferrules to the casing, this means consisting 50 in crimping the inner edges of the ferrules into suitable grooves formed in the casing of the fuse.

These and other advantages of my invention will be more readily understood by reference to the accompanying drawings, in which—

Figure 1 is a longitudinal section through my improved cartridge fuse;

Fig. 2 is a longitudinal section of the fuse shown in Fig. 1, and taken on the line 2—2 thereof;

Fig. 3 is a longitudinal section of a ferrule sleeve before it has been applied in position on the fuse casing;

Fig. 4 is a longitudinal section through one of the abutment thimbles before it has been applied to the fuse casing;

Fig. 5 is a perspective of one of the abutment thimbles before it has been applied to the fuse casing;

Fig. 6 is an end elevation of the cartridge fuse shown in Figs. 1 and 2;

Fig. 7 is a transverse section taken on the line 7—7 of Fig. 2;

Fig. 8 is a transverse section taken on the line 8—8 of Fig. 2; and

Fig. 9 is a side elevation of the fuse casing before the ferrules have been applied thereto.

The fuse casing 20, of fiber or other suitable insulating material, is provided near its ends with the grooves 21. Each of the ferrules applied to the ends of the casing 20 consists of three members: first, the abutment thimble 22, second, the ferrule sleeve 23, and, third, the ferrule plug 24. In assembling the various parts of the fuse which remain permanently in position the abutment thimbles 22, in the shape in which they are shown in Figs. 4 and 5, are slipped over the ends of the casing 20 with which they have a tight fit, the inwardly-extending abutment flange 25 of each thimble being brought into snug engagement with the corresponding end of the casing 20. From each abutment flange 25 an alinement tongue 26 (the object of which will be explained hereafter) has been upset, the alinement tongues 26 at opposite ends of the casing 20 being located diametrically opposite to each other. 100 The ferrule sleeves 23, in the form in which they are shown in Fig. 3, are then slipped into position so that they embrace the outer surfaces of the abutment thimbles 22, these

ferrule sleeves being moved inwardly until the shoulders 27 thereon engage the abutment flanges 25 of the abutment thimbles 22, the shoulders 27 being located between the 5 threaded portions 28 of the ferrule sleeves 23 and the inner plane skirt portions 29 thereof.

The next operation is to crimp the inner edges of the abutment thimbles 22 and the 10 ferrule sleeves 23 into the positions in which they are shown in Figs. 1 and 2, so that the inwardly-extending locking flanges 30^a and 31^a are thereby formed on the abutment thimbles 22 and the ferrule sleeves 23, respectively, these locking flanges engaging the grooves 21 in the casing 20.

The parts which I have just described, to-wit, the abutment thimbles 22 and the ferrule sleeves 23, are thus permanently fastened to the fuse casing 20. The remaining parts of the fuse which will now be described are removably placed in position so that on blowing of the fuse these parts may readily be removed and a new fuse link 25 placed in position.

A washer 30 provided with an alinement recess 31 in its periphery engages the abutment flange 25 in each of the ferrules. The alinement tongues 26 of the abutment flanges 30 25 extend into the alinement recesses 31, and are of substantially the same width as said recesses, so that it will be evident that the washers 30 can be placed only in a single predetermined position and are effectually 35 prevented from rotating by the engagement of the sides of the alinement tongues 26 with the sides of the alinement recesses 31.

The flat fusible link 32 extends diagonally through the casing 20, and through each of 40 the alinement recesses 31, the ends 33 of the link 32 being bent-over the outer faces of the washers 30. As most clearly shown in Fig. 1, the thickness of the link 32 which is capable of being used in the fuse is limited by 45 the distance between the inner edges of the alinement tongues 26 and the bases of the alinement recesses 31, it thereby becoming impossible to use in any particular fuse casing a link which is of greater thickness than 50 is proper for such fuse casing.

The ferrule plugs 21 having the slots 34 in their outer ends are screwed into the threaded ends 28 of the ferrule sleeves 23 until the inner surfaces of these ferrule plugs engage the bent-over ends 33 of the link 32. When 55 this takes place, it will be evident that the washers 30 are firmly forced against the abutment flanges 25 and all of the parts are firmly held in position. There is a slight 60 clearance between the threads of the ferrule plugs 21 and the threads of the outer portions 28 of the ferrule sleeves 23 in order to form restricted passages for the escape of gases when the fuse is blown. The apertures 65 35 are preferably provided in the ferrule

plugs 24 in order that the rating numbers 36 placed on the bent-over ends 33 of the link 32 may be readily visible.

After a fuse has been blown, thereby destroying the fuse link 32, it will be evident 70 that the latter may be readily renewed by first removing the ferrule plugs 24 and then removing the washers 30, after which a new link 32 may be placed in position within the casing 20, the washers 30 then brought into 75 the positions shown in Figs. 1 and 2, the ends 33 of the links bent over the outer surfaces of the washers 30, and the ferrule plugs 24 then screwed home, as above described.

It will be apparent to those skilled in the 80 art that many changes could be made in the detailed construction of the various parts which I have described without departing from the spirit or scope of my invention.

What I claim is:

1. In an inclosed safety fuse, the combination of a casing, a ferrule at the end of said casing, a washer within said ferrule and having a recess in its periphery, a fuse link having its end clamped between the 90 outer face of said washer and said ferrule, an abutment flange within said ferrule and against which said washer is seated, and an alinement tongue formed in said abutment flange and engaging the recess of said 95 washer, whereby the latter is alined in a predetermined position.

2. In an inclosed safety fuse, the combination of a casing, an abutment thimble fitting over the end of said casing, said abutment thimble having an inwardly-extending flange engaging the end of said casing, an alinement tongue projecting from said abutment flange, a ferrule sleeve fitting over said abutment thimble and having a portion extending beyond the end of said casing, a washer within the outer portion of said ferrule sleeve and engaging said abutment flange, said washer having an alinement recess in its periphery, said alinement recess being engaged by said alinement tongue, a fusible link within said casing and extending through the recess of said washer, the end of said link being bent over the outer face of said washer, and a ferrule plug 115 having threaded engagement with the outer portion of said ferrule sleeve and bearing against the bent-over end of said link, whereby the latter is securely clamped in position between the outer face of said 120 washer and said plug and the washer is brought into firm engagement with said abutment flange.

3. In an inclosed safety fuse, the combination of a casing having an exterior groove 125 near its end, an abutment thimble fitting over the end of said casing, said abutment thimble having an inwardly-extending abutment flange engaging the end of said casing, a ferrule sleeve fitting over the abutment 130

- thimble, the inner edges of said abutment thimble and said ferrule sleeve being crimped into the groove of said casing whereby said abutment thimble and said ferrule sleeve are locked in position, a washer within said ferrule sleeve and engaging the abutment flange of said abutment thimble, said washer having an aperture therein, a fusible link within said casing and passing through the aperture of said washer, the end of said link being bent over the outer face of said washer, and a plug fitting within the outer end of said ferrule sleeve and engaging the bent-over end of said link, whereby the latter is clamped securely against said washer and the washer is brought into firm engagement with said abutment flange.
4. In an inclosed safety fuse, the combination of a casing, an abutment thimble fitting over the end of said casing, said abutment thimble having an inwardly-extending abutment flange engaging the end of the casing, a ferrule sleeve fitting over said abutment thimble and having a shoulder engaging said abutment flange, said ferrule sleeve having its outer portion interiorly threaded, a washer within the outer portion of said ferrule sleeve and engaging said abutment flange, said washer having an aperture therethrough, a fusible link within said casing and passing through the aperture of said washer, the end of said link being bent over the outer face of said washer, and a plug having engagement with the threaded interior of the outer portion of said ferrule sleeve and bearing against the bent-over end of said link, whereby the latter is securely clamped in position between
- the outer face of said washer and said plug and the washer is brought into firm engagement with said abutment flange.
5. In an inclosed safety fuse, the combination of a casing having an exterior groove near its end, an abutment thimble fitting over the end of said casing, said abutment thimble having an inwardly-extending abutment flange engaging the end of said casing, an interiorly threaded ferrule sleeve fitting over the abutment thimble and having a shoulder engaging the outer end of said abutment thimble, the inner edges of said abutment thimble and said ferrule sleeve being crimped into the groove in said casing, whereby said abutment thimble and ferrule sleeve are securely locked in position, a washer within the outer portion of said ferrule sleeve and engaging said abutment flange, said washer having an aperture therethrough, a fusible link within said casing and passing through the aperture of said washer, the end of said link being bent over the outer face of said washer, and a plug having engagement with the threaded interior of the outer portion of said ferrule sleeve and bearing against the bent-over end of said link, whereby the latter is securely clamped in position between the outer face of said washer and said plug and the washer is brought into firm engagement with said abutment flange.

In witness whereof, I hereunto subscribe my name this 28th day of April, A. D. 1915.

ALFRED L. EUSTICE.
